Carpets

UNITED STATES PATENT OFFICE.

ALBERT COWELL, OF KIDDERMINSTER, ENGLAND.

DESIGN FOR A CARPET-PATTERN.

Specification forming part of Design No. 5,718, dated March 26, 1872.

To all whom it may concern:

Be it known that I, ALBERT COWELL, of Kidderminster, in the county of Worcester, in England, have invented a new and original Design for Carpets; and I do hereby declare that the following is a full, clear, and exact description thereof, which will enable others skilled in the art to make and use the same, reference being had to the accompanying photographic illustration forming part of the specification—

This invention relates to a new design of the several main figures in a carpet, of which there are three. The most prominent figure is composed of five elongated and graduating hexagons, that are separated from each other by

bands of foliage, as shown. Next in prominence is an octagon, containing a circular wreath of flowers and surrounded by scroll-work. Between the larger figures and the octagon are smaller figures, placed obliquely, each composed of an inner hexagon and of two squares attached thereto at diagonally opposite points. In every carpet the larger figures and octagons are to alternate in transverse as well as longitudinal rows.

I claim as my invention—

The design for carpets, as shown.

ALBERT COWELL.

Witnesses:
